M. TIBBE S.
HYDROCARBON MOTOR;
APPLICATION FILED MAY 6, 1916.

Patented Dec. 16, 1919.

UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

Specification of Letters Patent.

Patented Dec. 16, 1919.

1,325,058.

Application filed May 6, 1916. Serial No. 95,921.

To all whom it may concern:

Be it known that I, MILTON TIBBETTS, a citizen of the United States, and resident of Detroit, Wayne county, State of Michigan, have invented certain new and useful Improvements in Hydrocarbon-Motors, of which the following is a specification.

This invention relates to an improvement in hydrocarbon motors and particularly to 10 the carbureter and air intakes thereof.

When the air intake openings of the carbureter of a hydrocarbon motor are unprotected, a considerable amount of dirt and dust passes through the carbureter and, 15 into and through the motor and tends to score the cylinders, pistons, bearings and other parts of the motor. One of the objects of the present invention is to provide a novel protection or filter for the carbureter air intakes of a hydrocarbon motor.

Another object of the invention is to provide a readily removable air filter, the screen of which can be quickly changed.

Another object of the invention is to provide 25 a movably mounted filter together with means operable preferably from the driver's seat for withdrawing the filter from the carbureter openings, when desired to thus permit the unobstructed admission of 30 air to the carbureter.

Another object of the invention is to provide means for banking the air up in front of the carbureter air intakes to thereby increase the effectiveness of the latter.

Other objects will appear from the following description taken in connection with the accompanying drawings which form a part of the specification, and in which:

Figure 1 is a side elevation partly in 40 section of a hydrocarbon motor showing one embodiment of this invention;

Fig. 2 is a front end view of the same;

Fig. 3 is a detail view partly in section of the carbureter and filter; and

Fig. 4 is an enlarged section on the line 45 4-4 of Fig. 3.

In the drawings, 10 designates the hydrocarbon motor, here shown of the V-type having a crank case 11 and cylinder blocks 12 and 13 set at an angle to each other. At the front end of the motor 10 is a fan 14 driven by a belt 15 from a pulley 16 on the crank-shaft not shown.

In the valley of the motor intermediate the cylinder blocks 12 and 13 is mounted 55 a carbureter 17 from which the explosive mixture is led to the motor through an intake manifold 18. The carbureter 17 comprises a float chamber 19, a main air intake 20, and an auxiliary air intake 21.

Arranged adjacent the carbureter is an air filter 22, which covers the mouths of the main and auxiliary air intakes 20 and 21, and through which all air entering the carbureter may pass. In the embodiment illustrated the filter is a funnel shaped box 60 rectangular in cross section. The top, sides and front are made of imperforate material while the lower side, which inclines from front to rear is made of a screen 23, preferably of gauze or other foraminous material. The open rear end of the filter abuts against a flange 17' on the carbureter and when the filter is pressed tightly against said flange all of the air supplied to the carbureter must pass through the screen. 75

The screen 23 is mounted on a frame 23' which is removably held in place to cover the opening. In this embodiment the sides of the funnel shaped box are provided with 80 flanges 22' between which the frame 23' slides in place, as shown in Fig. 4, but it is obvious that other holding means could be employed.

If the screen is properly cleaned or 85 changed often enough, there will be no throttling of the air supply, but in case the screen should become clogged it may of course, be removed, or the filter may be withdrawn as a whole or raised from its 90 position over the carbureter intakes.

As shown, the filter is horizontally pivoted at 24 upon the carbureter and is held down with the rear opening against the carbureter by gravity and by a spring 25 or other suitable yielding means. A connection 26, which extends over the idle pulley 27 to the dash near the driver's seat is provided for raising the filter to the dotted line position shown in Fig. 1. If the screen becomes so dirty 100 as to choke the motor the driver can raise the filter by means of the connection 26, thus removing any obstruction to the air passage until such time as a new screen can be conveniently substituted or the old screen 105 cleaned.

- Provision is also made for banking up the air under the screen to increase the effectiveness of the carburetor action. One manner of carrying this out is shown in the drawing.
5. At the rear of the motor is fixed a vertical plate 28 secured to the cylinder blocks in any desired manner and shaped in a general way to the outline of the space between the cylinder blocks. (See Fig. 2). Extending from the upper edge of the plate 28 to the front of the carburetor is a second plate 29 suitably secured in place and closing the top of the valley behind the carburetor. The upper edge of the plate 28 has a rolled flange designated as 30 and the rear edge of the plate 29 may be slipped into place under the flange to prevent rattling. In addition to these inclosing plates there may be mounted a pair of plates 31 at the sides of the filter 22 to close the space between the filter and the sides of the cylinders. The rear plate 28 is here shown made of two similar sections hinged together at 28' to permit the easy removal thereof.
25. By thus inclosing the space between the cylinders it will be seen that the air delivered by the fan 14 will rush rearwardly between the motor cylinders and will be banked up under the screen thus creating a pressure at that point and forcing itself into the carburetor.
- It will be understood that other forms may be made without departing from the spirit or scope of the invention.
35. Having thus described my invention, what I claim and desire to secure by Letters Patent is:—
1. The combination with a carburetor having a main air intake and an auxiliary air intake, each of which has a receiving mouth, an air-filtering device arranged externally of said carburetor in position to filter the air entering both said mouths, and means supporting said device so as to permit the latter to move to and from coöperative relation with said mouths.
  2. The combination with a V-type hydrocarbon motor, of a carburetor arranged in the valley of the motor said carburetor having an air intake mouth arranged to receive air from said valley, and means arranged in said valley to divert the air passing through said valley into said mouth.
  3. In a V-type hydrocarbon motor, the combination with a carburetor positioned in the valley, of an air filter in front of said carburetor, and means in the valley to impede the free passage of air and thus bank up the air so as to increase the supply to be drawn upon by the carburetor.
  4. In a V-type hydrocarbon motor, the combination with a carburetor positioned in the valley of the motor, of an air filter in front of said carburetor, a hinged imperforate plate vertically placed at the rear of the motor, and an imperforate cover plate horizontally placed to inclose the portion of the valley between the hinged plate and the air filter.
  5. In a V-type hydrocarbon motor, the combination with a carburetor positioned in the valley of the motor, of an air filter in front of said carburetor, a hinged imperforate plate vertically placed at the rear of the motor, and an imperforate cover plate horizontally placed to inclose the portion of the valley between the hinged plate and the air filter, and removably secured to the cylinders.
  6. In a hydrocarbon motor, the combination with a carburetor, of an air filter for said carburetor composed of a member rectangular in cross section, open at the base and closed at the top, having three sides imperforate and the fourth foraminous.
  7. In a hydrocarbon motor, the combination with a carburetor, of an air filter for said carburetor composed of a member rectangular in cross section, open at the base and closed at the top, having three sides made of imperforate material and the fourth of gauze or other foraminous material.
  8. In a hydrocarbon motor, the combination with a carburetor, of an air filter for said carburetor composed of a member rectangular in cross section, open at the base and closed at the top having three sides made of imperforate material and the fourth of gauze or other foraminous material removably mounted on the imperforate sides.
  9. In a V-type hydrocarbon motor, in combination, a carburetor arranged with its air intake in the space between the cylinders, an air filter for said intake, and means for closing up the rear of said space to bank up the air against said filter.
  10. In a V-type hydrocarbon motor, in combination, a carburetor arranged with its air intake in the space between the cylinders, and means for closing up the rear of said space to bank up the air in front of said intake.
  11. In a hydrocarbon motor, in combination, a carburetor having an air intake, a filter over said intake, and means for forcing air against said filter.
  12. In a hydrocarbon motor, in combination, a carburetor having an air intake, a filter over said intake, and means for banking up the air against said filter.
  13. In a hydrocarbon motor, in combination, a carburetor having an air intake, a filter over said intake, and having its inlet opening downwardly, and means for banking up the air against said inlet.
  14. In a V-type hydrocarbon motor, the combination with a carburetor positioned in the valley formed by the cylinder blocks of the motor, of means mounted in said valley

to impede the free passage of air through the valley and to insure a supply of air to the carbureter from between the cylinder blocks.

5 15. In a V-type hydrocarbon motor, the combination with a carbureter positioned in the valley formed by the cylinder blocks of

the motor, of readily removable means mounted in said valley to impede the free passage of air through the valley and to insure a supply of air to the carbureter from between the cylinder blocks. 10

In testimony whereof I affix my signature.

MILTON TIBBETTS.
